UNITED STATES PATENT OFFICE.

LEROY THOMAS, OF MOMBACCUS, NEW YORK.

GEARING FOR WASHING-MACHINES.

1,107,727.

Specification of Letters Patent. Patented Aug. 18, 1914.

Application filed June 3, 1913. Serial No. 771,467.

To all whom it may concern:

Be it known that I, LEROY THOMAS, a citizen of the United States, residing at Mombaccus, in the county of Ulster and 5 State of New York, have invented certain new and useful Improvements in Gearing for Washing-Machines, of which the following is a specification.

My invention relates to gearing for converting a continuous rotary movement into a reciprocatory-rotary movement, and has particular reference to means of this character which are especially well adapted to operate the agitating or rubbing element of 15 a washing machine.

An important object of this invention is to provide means of the above mentioned character, which are simple in construction, and formed of a few parts, which are so 20 arranged that they do not interfere with the operator raising the lid or cover of the washing machine.

A further object of this invention is to provide means whereby the operating lever 25 may be angularly adjusted, to assume a convenient position for the individual operator.

A further object of my invention is to provide means of the above mentioned character, which are strong, durable, and operate in a highly satisfactory manner.

Other objects and advantages of this invention will be apparent during the course of the following description.

35 In the accompanying drawings forming a part of this specification and in which like numerals are employed to designate like parts throughout the same, Figure 1 is a side view of a washing machine, showing 40 my gearing applied thereto, Fig. 2 is a plan view of the same, Fig. 3 is a side view of a washing machine, taken at a right angle to Fig. 1, parts of the washing machine being broken away for the sake of illustration, 45 Fig. 4 is an enlarged perspective view of the operating lever and supporting bracket, and, Fig. 5 is a side view of the same.

In the drawings, wherein for the sake of illustration, is shown a preferred embodiment of my invention, the numeral 6 designates a main shell or casing of the washing machine, which is preferably circular in cross-section and decreases in diameter upwardly. The upper end of the main shell 55 or casing is normally closed by a vertically

swinging lid or cover 7, hinged as shown at 8.

Rigidly mounted upon one side of the main shell or casing 6 near the upper end thereof, is an open frame 9, having an opening 10 formed therethrough, for receiving the outer end of a rotatable stub-shaft 11. The inner end of the stub-shaft is rotatably mounted within a stationary bearing 12, fixed to the main shell or casing 6. Rigidly 65 mounted upon the rotatable stub-shaft 11 is a fly wheel 13, which does not extend beyond the upper end of the main shell or casing 6, as shown. Disposed inwardly of the fly wheel 13 is a small gear wheel or 70 pinion 14, rigidly mounted upon the rotatable stub-shaft 11, and engaging a large gear wheel or pinion 15, arranged there above. The upper large gear wheel 15 is rotatably mounted upon a stub-shaft 16, 75 which is rigidly connected with the upper portion of the main shell or casing 6. Disposed upon the inner side of the upper large gear wheel or pinion 15 is a bevel gear 17, which is rigidly connected therewith to 80 rotate with the same.

Rigidly connected with the upper portion of the main shell or casing 6 is a bracket 18, carrying a stub-shaft 19, upon which is pivotally mounted a segment 20, provided 85 with a depending crank 21.

The numeral 22 designates an operating lever, the lower end of which is preferably forked to straddle the segment 20. The free end of the forked portion of the operating lever 22 is apertured, as shown at 23 for receiving the stub-shaft 19, as shown. The forked portion of the operating lever 22 carries a clamping bolt 24, which operates through a curved slot 25 formed in the 90 segment 20. It is thus seen that by proper manipulation of the clamping bolt 24, the operating lever 22 may be locked to the segment 20 at desired angular positions with relation thereto. Pivotally connected with 95 the lower end of the depending crank 21 is a pitman 26, which is pivotally connected with the large gear wheel or pinion 15, as shown at 27. It is thus seen that by oscillating the operating lever 22, the same will 100 effect the rotation of the large gear wheel or pinion 15.

The lid or cover 7 is provided centrally thereof with a bearing 28, rigidly attached thereto by any suitable means. Rotatably 110

mounted within this bearing is a stub-shaft 29, the lower end of which extends into the main shell or casing 6 and is provided therein with an agitating or rubbing element 30, rigidly attached thereto. Rigidly connected with the upper end of the stub-shaft 29 is a gear or pinion 31, disposed within an open gear 32, carrying teeth 33, which engage the gear wheel or pinion 31, as shown. The open gear 32 is rigidly connected and preferably cast integral with one end of a lever 34, which is pivotally connected with the lid or cover 7 by means of a stub-shaft 35. Attention is called to the fact that the stub-shaft 35 is disposed between the ends of the lever 34, preferably approximately equi-distant from such ends. The outer end of the lever 34 is provided with a longitudinally extending slot 36, receiving a crank pin 37, which is rigidly mounted upon a bevel gear 38. This bevel gear is disposed below the lever 34 and is rotatably mounted upon a stub-shaft 39, which is suitably attached to the cover or lid 7. The bevel gear 38 engages the bevel gear 17, as shown.

The operation of the apparatus is as follows:—The operating lever 22 is oscillated which effects a continuous rotation of the large gear wheel or pinion 15, such rotation being transmitted to the fly wheel for maintaining the same steady. The gear wheel 15 rotates the bevel gear 17, which in turn rotates the bevel gear 38. The bevel gear 38 oscillates the lever 34, which is pivoted between its ends at 35. This oscillatory movement of the lever 34 causes the open gear 32 to be reciprocated, such open gear in turn imparting a reciprocatory rotary movement to the gear wheel 31. The reciprocatory rotary movement of the gear wheel 31 is imparted to the agitating or rubbing element 30. It is obvious that the cover or lid 7 may be readily raised or moved to its open position, such movement disengaging the bevel gears 17 and 38. Attention is called to the fact that the fly wheel 13 and associated elements are not mounted upon the cover or lid 7, whereby the weight of the same is taken off of the cover or lid, thus rendering it more easy to move the cover or lid to its open position. Attention is further called to the fact that the number of elements mounted upon the cover or lid 7, to rotate the agitating or rubbing element 30, is reduced to the minimum. It is to be understood that the form of my invention herewith shown and described is to be taken as a preferred example of the same, and that various changes in the shape, size and arrangement of parts may be resorted to without departing from the spirit of the invention or the scope of the subjoined claims.

Having described my invention, I claim:—

1. In apparatus of the character described, the combination with a relatively stationary

support, of a movable support pivotally connected therewith, an oscillatory lever pivotally connected between its ends with the movable support and having its outer end disposed adjacent one edge of the movable support and provided with a longitudinal slot and its inner end provided with gear teeth, a gear mounted upon the movable support adjacent the gear teeth to engage the same, a bevel gear mounted upon the movable support adjacent the said edge thereof and provided with a crank pin operating within the longitudinal slot, a bevel gear mounted upon the relatively stationary support and normally engaging the first named bevel gear and disengaging the same when the movable support is swung in one direction, and means to rotate the second named bevel gear.

2. In apparatus of the character described, the combination with a relatively stationary support, of a movable support pivoted to the relatively stationary support and adapted to be swung in a substantially vertical plane with relation thereto, a bevel gear rotatably mounted upon the movable support near the free edge thereof, a second bevel gear rotatably mounted upon the upper end of the relatively stationary support and detachably engaging the first named bevel gear, gearing mounted upon the movable support and driven by the first named bevel gear, and means to rotate the second named bevel gear.

3. In apparatus of the character described, the combination with a relatively stationary support, of a second support pivoted thereto and adapted to be moved to approximately horizontal and vertical positions, a bevel gear rotatably mounted upon the second support near the free edge thereof, a second bevel gear rotatably mounted upon the upper portion of the relatively stationary support and detachably engaging the first named bevel gear, an oscillatory lever pivotally mounted between its ends upon the second named support and provided at its outer end with a longitudinal slot, a pin carried by the first named bevel gear and operating within the longitudinal slot, gearing mounted upon the second named support and driven by the oscillatory lever, and means to rotate the second named bevel gear including a fly wheel.

4. In apparatus of the character described, the combination with a relatively stationary support, of a second support pivoted thereto, a bevel gear rotatably mounted upon the second support near one edge thereof and provided with a crank pin, an oscillatory lever pivoted between its ends to the pivoted support and provided at its outer end with an elongated slot to receive the crank pin, gearing connected with the inner end of the oscillatory lever to be driven thereby, a fly wheel rotatably mounted upon the side of

the relatively stationary support and extending below the same, a pinion rigidly connected with the fly wheel for rotation therewith, a second pinion rotatably mounted 5 upon the side of the relatively stationary support and engaging the first named pinion, a second bevel gear rigidly connected with the second named pinion for rotation therewith and detachably engaging the first

named bevel gear, and means to rotate the 10 second named pinion.

In testimony whereof I affix my signature in presence of two witnesses.

LEROY THOMAS.
